UNITED STATES PATENT OFFICE.

EARL S. GIBSON, OF RIDGEWOOD, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed November 21, 1924, Serial No. 751,218. Renewed January 3, 1927.

This invention relates generally to telephone exchange systems, and more particularly to telephone systems wherein automatic switching apparatus is employed in 5 whole or in part for the completion of conversational connections and especially to so-called semi-automatic systems.

An object of the invention is the provision of a more efficient method of transmitting 10 designations from an operator's position to a common receiving and registering device.

A feature of the invention relates to an impulse transmission mechanism whereby any one of a series of digital designations 15 may be sent from an impulse generating source to registering apparatus utilizing but one impulse period for the complete transmission of any digit.

Other inherent features and advantages 20 of the invention will become apparent after consideration of the following descriptions and the appended claims.

Referring to the drawing, Figs. 1 to 8 inclusive, when arranged in the manner 25 shown in Fig. 9, disclose a preferred embodiment of the invention and in sufficient detail to enable a complete understanding to be attained thereof.

Fig. 1 shows one of a number of incoming trunks terminating before an operator's position, as well as one of a plurality of cord circuits by means of which the operator completes connections to succeeding selective switches. This figure also discloses 35 certain controlling and supervising apparatus associated with the cord circuit.

Fig. 2 shows a portion of a special district selector switch by means of which the operator is enabled to extend calling lines in 40 any desired direction.

Fig. 3 illustrates a key set at the operator's position, and upon which numerical designations of wanted lines are manually recorded.

Fig. 4 in the upper left portion discloses 45 one of a number of sender selector switches employed for the purpose of associating an idle register sender with the operator's key set. This figure also shows impulse generating and controlling equipment for controlling the transmission of code impulses to the recording apparatus of a selected sender.

Fig. 5 shows in diagrammatic form various 50 connective devices by means of which common controlling mechanisms of different

kinds are interconnected. The connecting device shown in the center of this figure is a so-called sender connector which serves to interconnect a selected idle sender with an idle-marker, such as shown within the rectangularly enclosed space. The connective devices shown in the upper portion of this figure are so-called frame and trunk connectors which serve to associate the marker with a particular district switch and with 60 a particular group of trunks outgoing therefrom.

Fig. 6 shows the impulse recording apparatus and various controlling equipment located in the sender.

Fig. 7 discloses the several registers of the sender. The so-called office code registers are herein shown in comparative detail while the numerical and stations registers are represented by the rectangularly enclosed portion.

Fig. 8 shows an operator's talking and receiving set as well as various pieces of apparatus associated therewith.

Fig. 9 is a diagram showing the manner 80 in which the various figures of the drawing are to be arranged to produce a unitary circuit disclosure.

General description.

The invention as herein disclosed is particularly applicable to a telephone system of the general type disclosed in U. S. Patent No. 1,543,967, issued June 30, 1925 to S. B. Williams and E. S. Gibson. Since however, 90 this application is concerned mainly with the manner of generating, transmitting and recording of impulses, the operation of the various selective switches as well as the operation of the sender and the marker 95 and the various connecting devices will be referred to in a general manner. For a more detailed description of the construction and mode of operation of these portions of the exchange apparatus, reference may 100 be had to the patent of S. B. Williams and E. S. Gibson above referred to.

The special district switch 200 as well as the sender selector switch 400 may be preferably of the coordinate type such as 105 shown and described in the British Patent 183,438 issued to the Western Electric Company, Limited, accepted September 6, 1923.

The method of generating and transmit-

85

100

105

110

ting impulses herein described is shown in connection with a so-called special operator's equipment. When a subscriber dials the digit zero or when an operator's services are required for the completion of a connection, for example, a toll or long distance connection, a trunk is seized leading to the special operator's position. Upon the seizure of such a trunk, a visual signal is given to the operator that a call requires her intervention. She thereupon inserts the plug of an idle cord circuit into the jack associated with the calling signal and learns the wants of the calling subscriber. Under certain circumstances it may be that the calling subscriber is situated within the same exchange as the special operator and has dialed the digit zero with the intention of securing the aid of an operator in completing a connection. Under other conditions the calling signal may be actuated by the extension of a connection from a so-called long distance or from a toll point, which also requires the services of an operator for the completion of connections. Having learned the designation of the wanted line, the special operator proceeds to set up the same manually on the key set shown in Fig. 3.

As soon as the operator inserts the plug 150 in jack 151 the sender selector switch 400 is actuated to associate an idle register sender, such as shown in Figs. 6 and 7 with the operator's key set. At this time also the impulse generating and controlling equipment shown in Fig. 4 is brought into operation. Relays 401, 402, etc., by successive cycles of operation and release, control the association of each row of keys 301, 302, etc., in the proper sequence with the recording relays of the sender. The timing of each impulse is controlled by relays 406 and 407 which are designed to be relatively slow in both operating and releasing. Since but one impulse period is required for the transmission of each digit, it becomes necessary to provide means whereby the digits 0 to 9 may be recorded. This is taken care of by means of the recording relays 601, 602, 603, etc., in the sender. It will be observed that these impulse recording relays occur in pairs. The relays 601, 603 and 605 of each pair are designed not to operate when the resistance 310 which is relatively high is included in series with their windings whereas, relays 602, 604 and 606 are designed to operate both when the resistance 310 is connected in series with their respective windings or when these windings are connected directly to ground. When a particular row of keys as row 302 has been associated with the recording relays by means of a relay similar to relay 411 and the recording relays have been operated corresponding to the setting by the operator, the correspond-

ing connecting relay as 701 in the sender register circuit is operated. Relays 701, 702, etc., connect the contacts of the recording relays with the relays of the several registers 710, 720, etc., and the proper register relays are operated. For example, if key 305 is depressed, then when the impulse recording relays are associated with row 302 by means of relays 402 and 412, relays 602, and 606 are operated. Relay 606 brings about the operation of relay 701 and a circuit is thereupon closed for the operation of register relay 705. As soon as the register 710 is positioned, relay 721 operates and transfers the recording leads to the succeeding register 720. At the end of the first impulse period, as determined by the successive operation and release of relays 406 and 407, the recording relays which had been operated are now released and rendered associable with a succeeding row of keys. Rows 303, 304 and 305 and row 306 which correspond to the numerical designation are next associated in succession with the recording relays, which are in turn associated in sequence with the respective registers 720, 730, etc. While in practice there will be provided 10 keys in each row, for the purpose of securing simplicity in the drawing but five keys are illustrated in each row. In a similar manner only the route register 710 and the office code registers 720, and 730 and 740 are shown in detail, it being understood that the thousands, hundreds, tens, units and stations registers represented diagrammatically by the rectangularly enclosed portion 750 include register relays similar to relays 705, 706, etc.

When the route register 710 and the office code registers 720, 730 and 740 have been positioned, the connecting device 500 is selectively actuated to associate the sender with an idle outgoing marker or switch controlling mechanism as 580. The record on registers 710, 720, etc., is now transferred to corresponding registers 510, 520, etc., in the marker. At this time also the frame connector 550 and the trunk connector 560 are operated. Connector 550 associates the marker testing mechanism 570 with the particular district switch 200 wherein the cord 120 terminates, and the trunk connector 560 associates the same testing mechanism with a particular group of trunks outgoing from switch 200 leading in the desired direction. The marker having determined an idle link, giving access to an idle trunk, in the selected group, the proper horizontal magnet as 210 is operated and the cord 120 is connected to an outgoing trunk leading in the direction of the called office. The purpose of the row of routing keys 301 which position the registers 710 and 510 in sequence, will now be apparent. Should the called line be located

in an office which is accessible by means of a plurality of alternate routes through different tandem offices, then the operator by means of the row of keys 301, may determine which tandem office shall be employed in the completion of the connection, as described in detail in the copending application of S. B. Williams and E. S. Gibson, Serial No. 751,235, filed Nov. 21, 1924.

10 *Detailed description.*

It will be assumed for the purpose of description that the trunk 152 has been seized as a result of a subscriber dialing the digit zero. For a detailed description of the manner in which the dialing of a special digit serves to extend a calling line to an operator's position, reference may be had to U. S. Patent No. 1,517,331, issued December 2, 1924, to S. B. Williams. When such a trunk has been seized, an appropriate signal is given the operator in any well known manner and she thereupon inserts the plug of an idle cord circuit as 120 in the jack in which the trunk 152 terminates. The insertion of plug 150 in jack 151 causes relay 101 to operate in a circuit which may be traced from battery through the winding of said relay to the sleeve of plug 150, thence to the grounded sleeve conductor of trunk 152. Relay 101 in operating completes a circuit from ground at the armature and back contact of relay 102, outer contacts of relay 101, right inner contact of relay 103, winding of relays 104 and 105, left contacts of relay 111, through resistance 801 to battery. Relays 104 and 105 operate in this circuit and immediately close a locking circuit which is completed from the above traced battery through the windings of these relays in series, through the locking contact of relay 104 and thence to ground through the winding of relay 102. Relay 102 while included in this locking circuit does not operate however, since its winding is shunted by the previously traced ground for operating relays 104 and 105. Relay 105 at its right armature and front contact connects ground through the windings of relays 103, 107 and 106 in parallel. Relay 103 immediately closes a locking circuit through its left winding and locking contact, left armature and back contact of relay 112 to the grounded conductor 155. The operation of relay 103 removes the shunt from around the winding of relay 102 which now operates in series with relays 104 and 105. When relay 106 operated, the operator's talking set was connected through contacts of the said relay to the incoming trunk 152. At this stage of the connection the green lamp 108 is illuminated in a circuit completed from battery through the said lamp, left armature and back contact of relay 113, outermost contacts of relay 114, middle contacts of relay 115 to the

grounded conductor 155. The green lamp remains lighted in this circuit until the connection is disrupted.

When relay 101 first operated it completed a circuit for the start relay 431, traceable from battery through the winding of said relay, conductor 154, upper inner contacts of relays 109 and 116, outer contacts of relay 117 to the grounded conductor 155. In the manner described in detail in the above mentioned patent to S. B. Williams, No. 1,517,331, relay 431 brings about the selective operation of switch 400 whereby an idle sender which it may be assumed is the one shown in Figs. 6 and 7, is associated with the operator's key set. When magnet 432 energizes during the selective operation of switch 400, temporary holding ground is applied to conductor 451. This ground also causes the operation of frame test connecting relay 607 in a circuit traceable from battery through the winding of said relay, contacts of relays 608, 609 and 610, to the grounded conductor 451. Relay 607 causes the operation of frame test relay 608 in a circuit traceable from battery through the winding of relay 608, left contacts of relay 607, conductor 452 to ground at the armature of magnet 432. Relay 608 opens the above traced circuit of relay 607, but this relay being slow to release maintains its armatures attracted for an appreciable interval, during which the holding relay 611 operates in a circuit traceable from battery through its winding, locking contact of relay 608, left contacts of relay 607, to ground as above traced. Relay 611 locks to ground at the sender release relay 610.

Relay 109 is operated at this time in a circuit which may be traced from battery through the winding of said relay, right contacts of relay 113, through contacts of switch 400 to conductor 451, left contacts of relay 610, winding of relay 612, to ground at the armature of relay 611. Relay 109 in operating opens the original circuit of the start relay 431 and this relay releases. However, the connection is held through switch 400 by means of the continued energization of a horizontal magnet such as 408. The white supervisory lamp 110 is now lighted in a circuit completed from battery, through said lamp, lowermost contacts of relay 109, to ground at the outermost contacts of relay 115. The lamps 110 and 108 remain lighted until the connection to the called line is established.

The sender recording circuit is now associated with the operator's key set by means of the group of conductors 153. It will be assumed that the called line designation necessitates the depression of route key 311 and office code keys 305, 312 and 313 respectively. It will be further assumed that the line designation contains no stations digit. The operator therefore depresses a key in

each of the numerical rows 306, followed by start key 308. As soon as the operator depresses the start key 308, therefore, a circuit is completed from battery through the 5 winding of start relay 409, conductor 453 closed contacts 309 to ground. It will be noted that contacts 309 are closed whenever any key in row 307 is depressed. Relay 409 at its inner armature connects ground to 10 conductor 454, thence through the innermost contacts of relay 105, through the normal contacts and winding of relay 118 to battery. Relay 118 operates and immediately closes a locking circuit for itself to the 15 grounded conductor 155. Relay 409 also connects ground through its outer contacts thence through the left inner contacts of relays 407 and 421, left contacts of relay 422, lowermost armature and back contact 20 of relay 401, to battery through the winding of relay 411. Relay 411 immediately closes a locking circuit which may be traced from battery through its winding and locking contact, conductor 455, winding of relay 25 422, to ground as previously traced. Relay 422 does not operate in this circuit since its winding is shunted by the circuit for operating relay 411. With the relay 411 operated the initiation of the impulse timing 30 relays 406 and 407 is begun. The manner in which these relays function is as follows: Relay 406 upon energizing closes an operating circuit for relay 407 which being slow to operate requires an appreciable interval 35 for the attraction of its armatures. When it has completely attracted its armature, relay 407 connects a shunt around the winding of relay 406 which thereupon releases and at the end of a short interval relay 406 causes 40 the release of relay 407. This cycle of operation and release of relays 406 and 407 serves to time the transmission of each impulse from the operator's key set to the recording relays of the sender. Accordingly, 45 when relay 411 operates a circuit is completed from battery through the winding of relay 406, right contacts of relay 407, normal contacts of relay 421, upper armature and back contact of relay 401, left outer contacts of relay 411, to ground at the armature 50 of relay 423. When relay 406 has completely attracted its armatures a circuit is completed from battery through the winding of relay 407, right outer armature and front contact of relay 406, to ground at an armature 55 of relay 409. Relay 407 upon attracting its armatures shunts the winding of relay 406 by means of ground which is connected through contacts of relays 409 and 407 to the lower terminal of the winding of relay 406. Relay 406 commences to release and when it has completely retracted its armatures shunts the energizing circuit of relay 407 which in turn begins to release. 60 65 This cycle of operation and release of the

timing relays is repeated for each digit transmitted. Upon the operation of relay 407 a circuit is completed from battery, through the winding of relay 421, left outer contacts of relay 407 to ground at the 70 armature of relay 409. Relay 421 also closes a locking circuit which is completed through the left contacts of relay 406 to the same ground. Relay 421 in operating connects battery through its right contacts, thence 75 through the upper winding of relay 401, through the left outer contacts of relay 411 to ground at the armature of relay 423. Relay 401 immediately locks through its lower winding and locking contact to the same 80 ground. The operation of relay 401 at this time opens the original energizing circuit of relay 411 which now remains locked in series with relay 422 as above described, and the shunt being removed from this latter relay, 85 the same now operates.

Route key 311 having been depressed, an impulse circuit is completed from battery through the windings of relays 604 and 603, conductor 453 through contacts of switch 400, 90 contacts of relay 105, conductor 156, right middle contacts of relay 411, conductor 457, left contacts of key 311, high resistance 310, to ground. Since the resistance of this circuit is comparatively high, the marginal relay 603 does not operate, but relay 604 does operate. Another impulse circuit is completed at this time which may be traced from battery through the windings of relays 606 and 605, right contacts of relay 615, conductor 454, contacts of switch 400, outermost contacts of relay 105, conductor 157, right outer armature and front contact of relay 411, conductor 458, right contacts of key 311, resistance 310 to ground. Since the high 95 resistance 310 is connected in series with the winding of marginal relay 605, this latter relay does not operate. However, relay 606 does operate in the above traced circuit. With relay 606 operated, ground is connected 100 through the outer contacts of the said relay, contacts of relay 613, right armature and back contact of relay 721, winding of relay 701 to battery. Relay 701 connects the route 105 register relays 710 to contacts of the recording relays in Fig. 6. Since relays 604 and 606 alone are operated, register relay 706 is energized. The circuit for operating relay 706 may be traced from battery through the winding of the same, contacts of relay 701, conductor 751, left contacts of relay 602, left armature and front contact of relay 604, armature and back contact of relay 603, to ground at the armature of relay 606. Relay 706 in operating closes a locking circuit 110 for itself to the grounded conductor 456.

It will be noted that when relay 701 operated a locking circuit was completed for the same which may be traced from battery through the winding and locking contact of 115

relay 701, conductor 752, winding of relay 613 to ground at the armature of relay 606. While relay 613 is included in this circuit the same does not operate since it is shunted by the previously traced operating circuit of relay 701. However, when relay 706 is operated as a result of the transmission of the first impulse, a circuit is completed from battery through the winding of relay 721 5 thence through outer contacts of relay 706 to the grounded conductor 456. Relay 721 immediately locks through its winding and locking contact to the conductor 456, and at its right armature and back contact removes the shunt from around the winding of relay 613 and this relay now operates in series with relay 701. At the end of the first impulse period, relays 406 and 407 become released. With relays 406 and 407 normal, the 10 previously traced locking circuit of relay 411 is opened and this latter relay now releases. Relay 411 in releasing disconnects the recording relays from the key set, and relays 604 and 606 which had been operated there- 15 upon release. The release of relay 606 disconnects the holding ground from the windings of relays 613 and 701 which relays now release. The release of the timing relays 406 and 407 also opens the locking circuit of 20 relay 421 which, after a short interval, retracts its armatures. Relay 421 is designed to be slow releasing to permit disassociation of the recording relays 601, 602, etc., from one row of keys, before these relays are as- 25 sociated with a succeeding row of keys.

The first digit having been transmitted, the timing relays 406 and 407 initiate a second cycle of operation and release. At this time, however, relay 412 operates to associate the recording relays with the row of 30 keys 302. The circuit for operating relay 412 may be traced from battery through the winding of the same, lowermost armature and back contact of relay 402, lowermost 35 armature and front contact of relay 401, contacts of relay 422, inner armature and back contact of relays 421 and 407 to ground at the armature of relay 409. Relay 412 locks in a circuit traceable from battery, 40 through the winding and locking contact of relay 412, conductor 455, winding of relay 422, to the above traced ground. As hereinbefore described, however, relay 422 is at this time shunted and does not operate. Relay 406 now operates in a circuit traced from battery through its winding, right contacts of relay 407, normal contacts of relay 421, upper armature and front contact of relay 401, upper armature and back contact of relay 402 through the left armature and front contact of relay 412 to ground at the armature of relay 423. Relay 406 in turn causes the operation of relay 407 which upon operating shunts relay 406 and this 45 latter relay releases subsequent to which,

relay 407 also releases. With relays 406 and 407 operated during this second impulse period, relay 421 is energized in a circuit completed from battery through its winding, left outer contacts of relay 407, to ground at the armature of relay 409. Relay 421 locks as hereinbefore described and connects battery through its right contacts, thence through the upper winding of relay 402 to ground, through the left outer contacts of relay 412. The row of keys 302 is now associated by means of relay 412 with the impulse recording relays. Since key 305 is assumed to have been depressed, an impulse circuit is completed from ground 50 through resistance 310, right contacts of key 305, conductor 459, right outer armature and front contact of relay 412, conductor 157, outermost contacts of relays 105, contacts of switch 400, conductor 454, contacts of relay 615, to battery through the windings of relays 605 and 606. Relay 606 alone operates in this circuit because of the inclusion therein of high resistance 310. Another impulse circuit is also completed from 55 ground through resistance 310, left contacts of key 305, conductor 351, right inner contacts of relay 412, conductor 158, contacts of relay 105, contacts of switch 400, conductor 461, winding of relays 601 and 602 to 60 battery. Relay 602 alone operates in this circuit, because of the resistance 310 included in series with relay 601. As soon as relay 606 operates ground is connected through an armature and front contact of relay 606, 65 thence through contacts of relay 613, right armature and front contact of relay 721, right armature and back contact of relay 727 to battery through the winding of relay 702. In the manner already described, relay 702 completes a locking circuit for itself 70 which includes the winding of relay 613, and as previously described, relay 613 does not operate since its winding is shunted. With recording relay 602 operated a circuit 75 is completed from battery through the winding of register relay 725, contacts of relay 702, conductor 753, right armature and front contact of relay 602, armature and back contact of relays 604 and 603 to ground at the armature of relay 606. As hereinbefore described in detail, relay 725 locks to the holding conductor 456 and completes an energizing circuit for relay 727 which in 80 turn opens the shunt around the winding of relay 613 and relay 613 operates in series with relay 702. At the termination of the second impulse period relays 406, 407 and 421 are released thus bringing about the release of relay 412 and the consequent disconnection of the recording relays from the 85 key set.

When relay 421 retracts its armatures a circuit is completed for operating relay 413. This circuit is similar to that already de- 90

scribed for relays 411 and 412. Relay 412 also locks in series with relay 422 which however being shunted fails to operate at this time. Upon operation of relay 413, in a manner deemed to be already familiar, a circuit is closed for relay 406 which initiates the third impulse period. Relays 406 407 therefore undergo a third cycle of operation and release during which period impulses corresponding to the second digit of the office code are transmitted. Since key 312 is depressed an impulse circuit is completed from battery through the windings of relays 604 and 603, conductor 453, through contacts of switch 400 and relay 105 to conductor 156, thence through the right middle contacts of relay 413, left contacts of key 312 to ground. Another impulse circuit is completed and may be traced from battery through the windings of relays 606 and 604 thence through contacts of switch 400 and relay 105 through the right contacts of key 312, resistance 310 to ground. Since the resistance included in the first traced circuit is comparatively low both relays 603 and 604 are energized, whereas the high resistance 310 being included in the latter circuit, relay 606 alone is energized. In the manner thought to be now familiar, the operation of relay 606 causes the actuation of connecting relay 703 and register relay 729 operates in a circuit from battery through its winding, contact of relay 703, armature and front contact of relay 603, to ground at relay 606. The operation of relay 729 as already described causes the operation of relay 731, relay 731 in turn opening the shunt around the winding of relay 613 which operates in series with 703. At the termination of the third impulse period when relay 413 and the recording relays release, the locking circuit of relays 703 and 613 is broken and these latter relays release.

In a similar manner the registers 740 and 750 are associated in succession by means of relays similar to relays 401 and 411 with corresponding rows in the key set whereby the complete line designation is recorded upon these registers. When all the digits of the line designation have thus been transmitted a circuit is completed for relay 423 which may be traced from battery through the winding thereof, lower outer armatures and front contacts of relays 401, 402, 403, etc., in series thence to ground by way of conductor 462 as hereinbefore described. Relay 423 immediately closes a locking circuit which is completed through its locking contact, thence through the right outer armatures and back contacts of relays 411, 412, 413, in parallel, etc., through the right contacts of the depressed keys in corresponding rows and thence through resistance 310 to ground. With relay 423 operated ground

is connected through the right armature and front contact of the same, to conductor 463 thence in parallel through the windings of the key release magnets shown at the top of Fig. 3 to battery. The operation of these magnets causes the release of the depressed keys. When all the keys have been thus released, the above traced locking circuit for relay 423 is broken and this relay releases.

It will be noted that when relay 423 operated, the holding ground for relays 401, 402, etc., was removed and these relays released. It will also be noted that when contacts 309 opened as a result of the restoration of key 308, relay 409 released. The release of relay 409, disconnects at the outer armature thereof, the ground for operating the timing relays 406 and 407, thus preventing further operation of these relays. Thus the keyset shown in Fig. 3 and the control mechanism shown in Fig. 4 is entirely restored to normal.

When the office code register 740 has been positioned as described in detail hereinbefore, a circuit is completed from the ground conductor 456, left contacts of relay 728, left outer armature and back contact of relay 616, right contacts of relay 617, to conductor 457. Ground on conductor 457 serves to bring about the actuation of the sender connector 500. With the sender connector operated, the sender is associated with an idle marker as 580. The record is now transferred from registers 710, 720, 730 and 740 to corresponding registers 510, 520, 530 and 540. For a description of the manner in which connector 500 is selectively actuated, and for a description of how records are transferred from the sender to the marker, reference may be had to the patent to Warren W. Carpenter, No. 1,600,399, issued Sept. 21, 1926.

In the manner described in detail in the U. S. Patent No. 1,600,443, issued September 21, 1926 to S. B. Williams, frame connector 550 is actuated to operatively associate the switch 200, in which the cord 120 terminates, with the test mechanism 507. A test is therewith made of the horizontal links in switch 200, such as links 215, 216, etc., for the purpose of determining an idle one thereof. At this time also the trunk connector 560 is operated to associate the test mechanism 570 with a particular group of trunks leading in the desired direction.

Having determined an idle link in switch 200 giving access to a trunk in the selected group a vertical magnet as 218 and a horizontal magnet as 210 are energized and the cord 150 is connected with this idle trunk. For a detailed description of the manner in which the switch 200 is operated to complete connection of an operator's cord circuit with an outgoing trunk under control of the marker, together with a description

of the manner of releasing the connection after termination of conversation reference may be had to the copending application of S. B. Williams and E. S. Gibson, Serial No. 5 751,235, filed Nov. 21, 1924.

What is claimed is:

1. In a telephone system, an operator's position, a keyboard thereat, a controlling sender comprising a plurality of registers and an impulse recording mechanism said mechanism being adapted to be associated in succession with each of said registers, means for sending from said keyboard to said mechanism a plurality of impulses simultaneously to selectively actuate said mechanism, and means responsive to and in accordance with the actuation of said mechanism for positioning the register with which said mechanism is associated.
2. In a telephone system, an operator's position, a keyboard thereat, a controlling sender comprising a plurality of registers and an impulse recording mechanism, means for associating said mechanism in succession with each of said registers, means for sending simultaneously from said keyboard to said mechanism a plurality of impulses of variable character to selectively actuate said mechanism, and means responsive to and in accordance with the actuation of said mechanism for positioning the register with which the said mechanism is associated.
3. In a telephone system, an operator's position, a keyboard thereat, a controlling sender comprising a plurality of registers and an impulse recording mechanism consisting entirely of relays, said mechanism being adapted for association in succession with each of said registers, means for sending from said keyboard to said mechanism a plurality of impulses simultaneously to selectively actuate said mechanism, and means responsive to and in accordance with the actuation of said mechanism for positioning the register with which said mechanism is associated.
4. In a telephone system, a keyboard comprising rows of keys, a controlling sender comprising a plurality of registers and an impulse recording mechanism consisting of sets of relays, means for associating said mechanism with the registers of said sender in succession, means dependent upon the actuation of a key in any row for sending an impulse to each of said sets of relays simultaneously to selectively actuate the same, and means dependent upon and in accordance with the actuation of said sets of relays for positioning the registers with which said mechanism is associated.
5. In a telephone system, an operator's keyset comprising rows of keys, a plurality of controlling senders, each sender comprising a plurality of registers and an impulse recording device, a sender selector switch,

means for operating said sender selector switch to associate an idle sender with said key set, means for associating each of said rows of keys in succession with said recording device, means for associating in succession each of the registers of a selected sender with said recording device, means responsive to the actuation of any key in any row for sending simultaneously a plurality of code impulses to selectively actuate said recording device, a timing device for controlling the period of transmission of said plurality of impulses and for controlling the time of association of any of said rows of keys with said recording device, and means responsive to and in accordance with the selective actuation of said recording device for positioning the register with which said recording device is associated.

6. In a telephone system, an operator's keyset comprising rows of keys each row bearing a different group designation, a plurality of cord circuits, a register sender, a sender selector switch, means responsive to the operator's seizing an idle cord circuit for use for causing said selector switch to operate to associate an idle sender with said keyset, an impulse recording mechanism in said sender, means for associating said mechanism in succession with each of said rows of keys and with a corresponding one of the registers in said sender, means for sending from said keyboard dependent upon the setting thereof a plurality of impulses simultaneously to said mechanism to selectively actuate the same, and means responsive to and in accordance with the actuation of said mechanism for positioning the register with which said mechanism is associated.

7. In a telephone system, an operator's keyset comprising rows of keys each row bearing a different group designation, a controlling sender comprising a plurality of registers each associable with a corresponding one of said rows of keys, an impulse recording mechanism in said sender adapted to be associated in succession with each of said rows of keys and a corresponding register, means dependent upon the setting of any key in any row for sending a plurality of impulses simultaneously to said mechanism to selectively actuate the same, and means responsive to and in accordance with the actuation of said mechanism for positioning the register with which said mechanism is associated.

8. In a telephone system, an operator's keyset consisting of rows of keys, a plurality of controlling senders each associable with said keyset and each comprising a plurality of registers and an impulse recording mechanism, an impulse timing device comprising a pair of relays arranged to cyclically operate and release, means effective during a cyclical operation and release of

- said pair of relays for sending simultaneously a plurality of impulses from said keyset to selectively actuate said recording mechanism, means for associating the registers of said sender in succession with said recording mechanism, and means responsive to and in accordance with the selective actuation of said mechanism for positioning the register with which said mechanism is associated.
- 10 9. In a telephone system a controlling device, a sender comprising a plurality of registers and an impulse receiving mechanism, said mechanism being adapted to be associated in succession with each of said registers, means for simultaneously sending from said controlling device to said mechanism a plurality of impulses to selectively actuate said mechanism, and means responsive to and in accordance with the actuation of said mechanism for positioning the register with which said mechanism is associated.
- 15 10. In a telephone system a controlling device, a sender comprising a plurality of registers and an impulse receiving mechanism, said mechanism being adapted to be associated in succession with each of said registers, means for simultaneously sending from said controlling device to said mechanism a plurality of impulses to selectively actuate said mechanism, and means responsive to and in accordance with the selective actuation of said mechanism for positioning the register with which said mechanism is associated.
- 20

ister with which said mechanism is associated.

10. In a telephone system, a primary registering device, a controlling sender comprising a plurality of secondary registers and an impulse recording mechanism, said mechanism being adapted to be associated in succession with each of said registers, means for simultaneously sending from said primary registering device to said mechanism a plurality of impulses to selectively actuate said mechanism, and means responsive to and in accordance with the selective actuation of said mechanism for positioning the register with which said mechanism is associated.

In witness whereof, I hereunto subscribe my name this 14th day of November A. D., 1924.

EARL S. GIBSON.
